UNITED STATES PATENT OFFICE.

JOHN MINOR BOTTS LEWIS, OF LYNCHBURG, VIRGINIA.

ANIMAL-STANCHION.

1,311,658.

Specification of Letters Patent.

Patented July 29, 1919.

Application filed April 19, 1918. Serial No. 229,597.

To all whom it may concern:

Be it known that I, JOHN M. B. LEWIS, a citizen of the United States, residing at Lynchburg, in the county of Campbell and State of Virginia, have invented certain new and useful Improvements in Animal-Stanchions, of which the following is a specification.

My invention relates to improvements in animal stanchions.

An important object of the invention is to provide simple and reliable means to hold or lock the stanchion against turning movement upon its vertical axis, when it is opened, but allowing of the free turning movement of the stanchion upon its vertical axis, when it is closed.

A further object of the invention is to provide a stanchion of the above mentioned character, so constructed that the opposite sides thereof open in opposite directions, thus suitably closing the spaces in the stall upon opposite sides of the stanchion, and dispensing with the employment of the ordinary stop rod or element ordinarily used in connection with the stanchion which opens at one side only.

A further object of the invention is to provide a stanchion of the above mentioned character, having means for properly retaining the same in position, but allowing of substantial movements thereof in all directions for the convenience of the animal, while standing or lying down.

A further object of the invention is to provide flexible connections for retaining the stanchion in the desired position, while in the opened or closed condition, which connections are adjustable to throw the stanchion forwardly or rearwardly.

Other objects and advantages of the invention will be apparent during the course of the following description.

In the accompanying drawings forming a part of this specification and in which like numerals are employed to designate like parts throughout the same,

Figure 1 is a perspective view of a stanchion embodying my invention, showing the same locked in the closed position, and in use in a stall,

Fig. 2 is a perspective view of the stanchion, in the open position,

Fig. 3 is a plan view of the attaching elements, the stanchion being omitted,

Fig. 4 is a central vertical sectional view

through a supporting rod and associated elements, parts being shown in elevation,

Fig. 5 is a detail section through a pivotal connection between the stanchion arms and anchor member,

Fig. 6 is a side elevation of the pivoted ends of the upper and lower arms constituting one side of the stanchion.

In the drawings, wherein for the purpose of illustration is shown a preferred embodiment of my invention, the numeral 10 designates the floor of a stall, having a curb 11, forwardly of which is arranged a manger 12 for receiving the feed.

The numeral 13 designates vertical posts or pipes, secured at their lower ends to the curb 11. At their upper ends the posts 13 are connected through the medium of T-couplings 14, with a horizontal pipe or support 15.

The numeral 16 designates stall partitions which may be formed of longitudinally curved pipes, the lower ends of which are secured to the floor 10 and the upper ends 80 to the posts or pipes 13 by means of couplings 17.

The stall hereinbefore described is of the well known construction and forms no part of the present invention but is shown for 85 the purpose of more fully explaining the construction and use of my stanchion to be next described.

The numeral 18 designates side members of my improved stanchion as a whole, both 90 of which are adapted to open outwardly. Each side member 18 embodies upper and lower arms or sections 19 and 20. The lower ends of the arms 19 are preferably provided with a pair of spaced apertured 95 knuckles 21, receiving apertured knuckles 22, formed upon the upper ends of the arms 20. The knuckles 21 and 22 are pivotally connected by pins 23 or the like. It is thus apparent that these apertured knuckles afford 100 hinge connections between the arms 19 and 20, which allow the same to swing transversely of the stall but positively prevent the arms from swinging at a right angle to this direction. Any other suitable means 105 may be employed for effecting this hinge connection.

Means are provided to lock the arms 19 and 20 together, preferably at a point near their hinged connections, such means comprising sliding bolts 24, operating within guide lugs 25, secured to the arms 19. The

bolts 25 are moved downwardly by springs 26. The lower ends of the bolts are adapted for insertion within sockets 27 rigidly secured to the upper portions of the arms 20. 5 The upper ends of the bolts preferably carry rings 28 or the like so that the bolts may be conveniently elevated. It is thus seen that when the bolts 24 are inserted within the sockets 27 they will serve to rigidly connect 10 the arms 19 and 20 thereby positively preventing the same from swinging upon their hinged connection.

At their upper ends, one arm 19 carries a pair of spaced knuckles 29 for receiving 15 therebetween a knuckle 30 carried by the other arm 19. These knuckles are pivotally connected by means of a pin 31, passing through openings in the forked head 32 secured to the lower end of an attaching element or rod 33. It is thus apparent that the 20 upper ends of the arms 19 are pivotally connected with the attaching rod 33 and are adapted to be swung laterally in the plane of the stanchion, as clearly illustrated in 25 Fig. 2. The attaching element or rod 33 is provided upon one side with a longitudinally extending key or rib 34, having a lower end 35 spaced a substantial distance from the lower end thereof or from the 30 forked head 32. The attaching element or rod 33 is adapted for insertion through a socket 36, having a main circular opening or bore 37 and a slot 38, at one side thereof, for receiving the key 34. The socket 36 is 35 carried by a rod 39, adapted for insertion within the transverse tubular element of a cross-coupling 40, and detachably clamped therein by a bolt 41. The rod 39 has a plurality of openings 42 formed therein, for 40 receiving the bolt 41, whereby the rod 39 may be longitudinally adjusted. If desired, the rod 39 may be withdrawn from the rear end of the cross-coupling 40 and inserted into the opposite or forward end thereof for 45 a purpose to be more fully described.

As more clearly shown in Figs. 2 and 4 the numeral 43 designates a latch or lock element, pivoted to the rod 39, as shown at 44. This latch element is provided at its 50 forward end with a head 45, adapted when in the lower position, to be disposed beneath the lower end 35 of the key 34, thereby positively locking the attaching element or rod 33 against downward movement. This 55 latch or lock element 43 is preferably employed in connection with the bolts 24, while these bolts may be dispensed with and the element 43 employed alone with some degree of success.

60 One arm 20 is provided at its lower end with a pair of spaced apertured knuckles 45', receiving therebetween an apertured knuckle 46 carried by the other arm 20.

The apertured knuckles are pivotally connected by a transverse pin 47, also passing

through the sides of a U-shaped socket 48, receiving these apertured knuckles. This U-shaped socket is provided in its bottom or transverse member 49 with an opening, pivotally receiving the shank of an eye-bolt 50 which is swiveled therein. The eye-bolt 50 is preferably horizontally elongated and receives a similar eye-bolt 51, in interlocking engagement therewith. The eye-bolt 51 has a shank 52.

The numeral 53 designates adjustable attaching links, provided at corresponding ends with apertured heads 54, the shank 52 extending through the apertures of these heads to be swiveled therein, the shank 80 carrying a nut 55 at its lower end. The links 53 are provided with a plurality of spaced apertures 56, adapted for receiving anchor bolts 57, preferably secured within the curb 11. It is thus apparent that these 85 anchor bolts may be inserted in a selected pair of the openings 56, thereby throwing the connecting links rearwardly or forwardly, and as indicated in dotted lines, these connecting links may be reversed so 90 that their apertured heads 54 will extend forwardly of the curb instead of rearwardly. The function of this construction is to provide means to forwardly and rearwardly adjust the point of connection of the lower 95 portion or end of the stanchion, as will be found advantageous, in connection with cows of different lengths. The rod 39 is adjustable forwardly and rearwardly, as above stated, so that the point of support of the 100 upper end of the stanchion may be correspondingly adjusted forwardly and rearwardly, and when the links 53 are extended forwardly instead of rearwardly the rod 39 is inserted in the forward end of the cross- 105 coupling 40 instead of the rear end.

In the use of the apparatus, when the stanchion is in the closed position, as illustrated in Fig. 1, the attaching element or bolt 33 is elevated, and the key 34 is arranged wholly above the socket 36, and out of the slot 38. It is therefore apparent that the stanchion is free to turn upon its vertical axis, the eye-bolts 50 and 51 also allowing of this swinging or turning movement, besides allowing the lower end of the stanchion to partake of substantial movements in all directions. The movements of the stanchion in all directions, are permitted by the swinging movements of the attaching element or 115 rod 33 in the opening 37, which is tapered and increases in diameter downwardly. When the stanchion is in the closed position, the locking element or latch 43 is disposed beneath the lower end 35 of the key 120 34, and the bolts 24 are inserted within the sockets 27, whereby the arms 19 and 20 are securely locked together and against outward or spreading movement.

To open the stanchion, the same is first 130

slightly elevated, to allow the element 43 being swung to the upper position, and upon the slight downward movement of the stanchion this element will contact with the 5 side of the rib or key 34. The bolts 24 are now moved upwardly and withdrawn from the sockets 27, at which time the opposite side members of the stanchion are adapted to be moved outwardly or away from each 10 other. As both side members 18 move outwardly it is obvious that the open stanchion will sufficiently close the opening or space between the vertical post 13, whereby the stop A, shown in dotted lines, and employed with stanchions opening on side only, 15 may be dispensed with.

It is to be understood that the form of my invention herewith shown and described is to be taken as a preferred example of the 20 same, and that various changes in the shape, size, and arrangement of parts may be resorted to without departing from the spirit of the invention or the scope of the subjoined claims.

25 Having thus described my invention, I claim:

1. In apparatus of the character described, a support, a socket connected with the support and having a laterally extending slot, a stanchion comprising side members each of which includes a pair of pivoted arms, an attaching element pivotally connected with the upper arms of the stanchion and loosely mounted within the socket 30 85 to turn and move longitudinally therein and having a laterally extending key to enter the slot when the attaching element is lowered, means to prevent the entrance of the key into the slot, and anchor means pivotally connected with the lower end of the lower arms of the stanchion.

2. In apparatus of the character described, a support, a socket connected with the support, a stanchion having pivoted 45 arms adapted to be moved to opened and closed positions; an attaching element connected with the upper end of the stanchion and loosely mounted within the socket to turn therein when in the elevated position 50 and having means to lock the same against turning movement when the attaching element is moved downwardly with relation to the socket, and anchor means connected with the lower end of the stanchion.

55 3. In apparatus of the character described, a support, a stanchion arranged near and beneath the support and adapted to be opened and closed, and a single reciprocatory device connecting the upper end of the stanchion with the support and adapted to turn upon a vertical axis and to be raised and lowered and adapted to permit of the turning movement of the stanchion when said device is in the upper position and to

lock the stanchion against such turning 65 movement when in the lower position.

4. In apparatus of the character described, a support, a stanchion loop for receiving the neck of the animal therein arranged near the same and comprising oppositely arranged side members, each side member of the loop including upper and lower arms, means to pivotally connect the adjacent ends of each pair of upper and lower arms, means disposed near each pivot 70 75 means to lock each pair of upper and lower arms against swinging movement upon the pivot means, and means for connecting the upper end of the stanchion with the support.

5. In apparatus of the character described, a support, a stanchion arranged near the same and comprising oppositely arranged members, each member including a pair of upper and lower arms, means to 85 pivotally connect the adjacent ends of the pair of upper and lower arms, means arranged near the pivot means to lock the pair of upper and lower arms together against swinging movement upon the pivot means, 90 means adapted to be bodily raised and lowered for connecting the upper end of the stanchion with the support so that the stanchion is free to turn upon its vertical axis when closed and held against such turning 95 movement when open, and separate means to lock the last named means against downward movement.

6. In apparatus of the character described, a support, a stanchion arranged 100 near the same and adapted to be opened and closed, means adapted to be bodily raised and lowered for connecting the upper end of the stanchion with the support so that the stanchion is free to turn upon its 105 longitudinal axis when closed and locked against such turning movement when open, means to lock the connecting means against downward movement, and anchor means connected with the lower end of the stanchion.

7. In apparatus of the character described, a support including a coupling having its opposite ends open, a substantially horizontal shaft adapted to be inserted into 115 either end of the coupling and carrying a socket, a stanchion arranged near the shaft and adapted to be opened and closed, a reciprocatory element arranged in the socket for connecting the upper end of the stanchion with the shaft so that the stanchion is free to turn upon its vertical axis when closed and locked against such turning movement when open, and adjustable anchor means connected with the lower end of the 120 125 stanchion.

8. In apparatus of the character described, a cross-coupling having the ends of

one pair adapted for the reception of supporting members, a shaft adapted to be inserted within either end of the other pair, means to lock the shaft in longitudinal adjustment within such end, a socket formed upon the shaft, a stanchion arranged near and beneath the socket and having pivotally connected arms adapted to be moved to opened and closed positions, an attaching element pivotally connected with the upper ends of the arms of the stanchion and loosely mounted within the socket to turn and move longitudinally therein, means whereby the attaching element may be held in the upper position and be free to turn within the socket and for locking the attaching element against turning movement when lowered within the socket, and anchor means connected with the lower end of the stanchion.

9. In apparatus of the character de-

scribed, a supporting element provided with a socket having a laterally extending opening, a suspension element mounted to slide within the socket and having a longitudinally extending key to enter the laterally extending opening when the attaching member is lowered, a stanchion connected with the attaching element and comprising pairs of pivoted arms, bolts carried by the corresponding arms near their pivots, and sockets carried by the other arms near their pivots and adapted for the reception of the bolts so that the arms are locked at their pivots against swinging movement. 35

In testimony whereof I affix my signature in presence of two witnesses.

JOHN MINOR BOTTS LEWIS.
